his Attorney

UNITED STATES PATENT OFFICE.

ERNEST RAPATTONI, OF LOS ANGELES, CALIFORNIA.

DESIGN FOR AN AUTOMOBILE TRAFFIC-SIGNAL.

56,193.

Specification for Design.

Patented Aug. 24, 1920.

Application filed June 7, 1920. Serial No. 387,194. Term of patent 7 years.

To all whom it may concern:

Be it known that I, ERNEST RAPATTONI, a citizen of the United States, residing at Los Angeles, in the county of Los Angeles, State of California, have invented a new, original, and ornamental Design for an Automobile Traffic-Signal, of which the following is a specification, reference being had to the accompanying drawing, forming part thereof.

The figure is a perspective view of an automobile traffic signal, showing my new design.

I claim:

The ornamental design for an automobile traffic signal, as shown.

ERNEST RAPATTONI.

Witnesses:

VIRGINIA BERNINGER,
FLORENCE EBRGOTT.
